UNITED STATES PATENT OFFICE

NORMAN W. CUMMINS, OF LOUISVILLE, KENTUCKY

HOOD FASTENER

Application filed February 9, 1929. Serial No. 338,671.

This invention relates to devices for yieldingly holding the hood of a motor vehicle detachably in place and its object is to provide an arrangement whereby the lower edge 5 portion of the hood is yieldingly held against vibration and consequent rattling. A further object of the present invention is to provide an arrangement which is simple in construction and cheap to manufacture 10 and is readily applicable to a hood fastener of an old and well known construction and to provide certain other new and useful features, all as will hereinafter more fully appear.

15 With the above and other ends in view the invention is comprised in the matters herein-after set forth and more particularly pointed out in the appended claims, reference being had to the accompanying drawings, in which

20 Figure 1 is a vertical section through a device illustrative of an embodiment of the present invention and showing the same in operative position in connection with a motor vehicle hood and adjacent parts;

25 Figure 2 is a section substantially upon the line 2—2 of Figure 1, and

Figure 3 a horizontal section substantially upon the line 3—3 of Figure 1.

As illustrative of an installation of the invention on a motor vehicle, 1 indicates a frame member of the vehicle which extends lengthwise at the side of the hood 2 which is provided to enclose the engine, not shown.

This hood 2 is provided with the usual bead 3 along its lower edge for the purpose of stiffening and strengthening the edge of the hood and as commonly constructed, this edge bead of the hood is adapted to seat upon an angle strip 4 secured along the inner edge 40 of the frame member 1 when the hood is in closed position with the bead outside of and against the upstanding flange of the angle strip.

Any suitable form of hood fastener may 45 be employed but as illustrative of a construction to be used in connection with the present invention and which is now commonly used on motor vehicles, a spring barrel 5 is shown within which is a rod 6 having a ball shaped head 7 at its lower end to engage

within a suitable socket member 8 secured in place upon the frame member 1 so that the rod and barrel may have a universal connection with the frame member. Within the barrel 5 and sleeved upon the rod 6 is a 55 coiled spring 9 interposed between the closed end of the barrel and a stop washer 10 which is attached to the upper end of the rod by providing a groove 11 in the rod which groove forms a neck portion to be engaged by the washer which has a lateral slot so that the washer may be slipped into the groove and when in place within the barrel 5 will be held upon the rod to move therewith with the spring 9 in compression between said 60 washer and the closed lower end of the barrel.

The upper end of the barrel is closed by a handle member 12, said handle member being formed with a socket to receive the screw-threaded upper end of the barrel, and this handle member is also provided with a laterally extending lug or prong 13 to engage within a suitable socket or loop 14 firmly secured to the outer side of the hood 2.

The spring 9 therefore exerts a force at all times to draw the hook 13 into firm engagement with its socket on the hood and thus detachably and firmly hold the edge of the hood seated upon the angle strip 4.

The above described hood fastener is of a well known construction but it has been found that in use, the lower edge of the hood will vibrate and rattle as it is held downwardly by the hood fastener but is not held firmly against the upstanding flange of the angle strip 4 at all times.

The present invention aims to overcome this defect by providing a socket member to receive and hold the head 7 of the rod 6, which socket member 8 is in the form of a housing containing a sleeve 15 which is free to move lengthwise in the housing and has an opening fitting the rod 6 and through which the rod extends. In the upper side of the casing 8 is a longitudinal slot 16 through which the rod 6 extends and interposed between an end wall 17 of the casing 8 and the head 7 on the rod is a coiled spring 18 which is placed in this position under compression 100

and exerts a yielding force to move the sleeve 15 and also the lower headed end of the rod toward the lower beaded edge 3 of the hood. An abutment or bracket 19 is secured to the 5 outer face of the hood and projects laterally therefrom toward the barrel 5. This bracket is formed with an end seat 20 in which is seated a cushion member 21 of rubber or other suitable material to engage the side of the barrel 5 when the hook 13 of the handle 10 12 is engaged with the socket 14 and the hood is fastened in place thereby. The bracket 19 is of such a length that when the hood fastener is tilted toward the hood in order 15 to engage its hook 13 with the socket on the hood, the lower end of the rod 6 and barrel 5 will be forced outwardly away from the hood by said barrel coming into engagement with the seat on the bracket 19. This outward movement of the lower end of the rod 20 compresses the spring 18 and therefore this spring exerts a yielding force at all times tending to swing the lower end of the rod and barrel toward the hood and press the 25 barrel firmly to its seat on the bracket 19. The lower edge portion of the hood is therefore forced inwardly by the action of the spring 18, and the bead 3 held firmly in contact with the upstanding flange of the angle strip 4. Vibration of this lower edge portion of the hood is therefore effectually prevented.

Obviously changes in the particular construction and arrangement of the housing 8 33 and the other parts which cooperate in holding the hood fastener pressed laterally toward the lower edge portion of the hood, may be varied to suit the particular construction of hood fastener and other conditions of installation. I do not therefore wish 40 to limit myself to the particular construction and arrangement shown, except as set forth particularly in the appended claims.

Having thus fully described my invention 43 what I claim is:

1. In a hood fastener including a member having means at its upper end to detachably engage a loop on a hood and including a rod having a ball at its lower end, a socket member to receive said ball and permit movement 50 thereof toward and from the hood, a spring to yieldingly force said ball and lower end of said rod toward the lower edge portion of said hood, and means projecting laterally from the hood adjacent its lower edge to be engaged by the lower end portion of the fastener member.

2. The combination with a hood fastener, adapted for pivotal attachment at its lower 60 end to a fixed support adjacent the lower edge portion of a hood and for detachable engagement with said hood at its upper end, said fastener including a spring for exerting a downward pull on said hood, and a rod having a ball for pivotally attaching said fasten-

er to said fixed support, of a socket member adapted to receive said ball and to be secured to said support, and means within said socket yieldingly holding said ball moved relative to its socket toward said hood to exert a pressure against the lower edge portion of said hood.

3. A device for the purpose described and as characterized in claim 2, and wherein said socket member has a slot through which said rod extends and a spring is interposed between said ball on said rod and the outer end of said socket.

4. A device of the character described and as characterized in claim 2, said device including a member slidable in said socket and having an opening in its upper side through which the rod extends with the ball on said rod within said sliding member, a spring within said socket member to move said sliding member and a member on the lower portion of the hood to oppose the action of said spring.

5. In a hood fastener including a member having means at its upper end to detachably engage a loop on a hood and including a rod, a fixed housing adjacent said hood, a sleeve 90 slidable in said housing, the lower end of said rod extending through said housing into said sleeve, said housing being slotted to permit sliding of said rod relatively thereto, and a spring mounted in said housing and engaging said lower end and adapted to move said end towards the hood.

6. In a hood fastener including a member having means at its upper end to detachably engage a loop on a hood and including a rod, a fixed housing adjacent said hood, a sleeve 100 slidable in said housing, the lower end of said rod extending through said housing into said sleeve, said housing being slotted to permit 105 sliding of said rod relatively thereto, a spring mounted in said housing and engaging said lower end and adapted to move said end towards the hood, and means for limiting the movement of said rod towards the hood.

In testimony whereof I affix my signature.
NORMAN W. CUMMINS.
